Louis Whitman, London, England

Application December 31, 1947, Serial No. 143,465
In Great Britain August 20, 1947

Term of patent 7 years

(Cl. D4—3)

To all whom it may concern:

Be it known that I, Louis Whitman, a citizen of Great Britain, residing at London, W.1, England, have invented a new, original, and ornamental Design for a Tooth Paste and Toothbrush Holder, of which the following is a specification, reference being had to the accompanying drawing, forming part thereof.

In the drawing:

Fig. 1 is a perspective view of a tooth paste and toothbrush holder, showing my new design.

Fig. 2 is a side elevational view of the same.

Fig. 3 is a front view of the same.

Fig. 4 is a side elevational view of the same.

Fig. 5 is a top plan view of the same.

I claim:

The ornamental design for a tooth paste and toothbrush holder, as shown.

LOUIS WHITMAN.
